UNITED STATES PATENT OFFICE.

CHARLES W. MOFFETT, OF FLUSHING, AND MARK R. BRINEY, OF BROOK HAVEN, NEW YORK, ASSIGNORS TO BRINARD SALES AND CONSTRUCTION COMPANY, OF NEW YORK, N. Y., A CORPORATION OF NEW YORK.

SWITCH HEATER.

Application filed February 12, 1927. Serial No. 167,636.

This invention relates to railway equipment and, with respect to its more specific features, to railway switches.

One of the objects of the invention is the provision of a practical apparatus wherewith normal operation of a railway switch may be assured under weather conditions which might otherwise prevent.

Another object of the invention is the provision of an apparatus of simple construction adapted readily to be closely associated with standard types of switches for preventing or removing accumulation of snow and ice in position obstructive of normal operation of the switches.

Another object of the invention is the provision of a practical heater adapted to be mounted between the tie and the rails without impairing the efficiency of either, and without injuring either.

Another object of the invention is the provision of a simple heating apparatus adapted so to be associated with a switch that, under all conditions of weather, a quantity of heat sufficient to melt obstructive snow and ice, will positively be transmitted to the air space between the stock rail and the switch rail.

Another object of the invention is the provision of a practical apparatus adapted, under all conditions of weather, positively to assure heating of the switch rails and of the stock rails adjacent the switch.

Another object of the invention is the provision of a heater, simple and strong in construction, and efficient in operation, which will maintain operative condition under heavy loads or shocks while positively distributing heat to the switch.

Another object of the invention is the provision of a practical construction of heater adapted, as a component part of the tie, to support the rails.

Another object of the invention is the provision of a practical and efficient apparatus adapted to heat the switch throughout practically its full length.

Other objects of the invention will be in part obvious and will in part appear hereinafter.

The invention accordingly comprises the features of construction, combinations of elements, and arrangement of parts, which will

be exemplified in the construction herein-after set forth and the scope of the application of which will be indicated in the claims. 55

For a fuller understanding of the nature and objects of the invention, reference should be had to the following detailed description taken in connection with the accompanying drawing, in which:

Fig. 1 is a diagrammatic plan view of a railway switch embodying the invention, certain parts being broken away for clearer disclosure. 65

Fig. 2 is a perspective view, partly in section, and enlarged over Fig. 1, showing the invention as embodied in one form of switch equipment.

Fig. 3 is a view similar to Fig. 2, showing the invention embodied in a somewhat modified form of switch equipment. The details of Fig. 3 are the same as that illustrated in Fig. 1. 70

Fig. 4 is an enlarged plan view, partly in section, of a railway tie associated with the detail type of heater illustrated in Fig. 3.

Fig. 5 is a side view of the heater of Fig. 4, partly in section.

Fig. 6 is a cross section of Fig. 4 on the line 6—6.

Fig. 7 is a detail.

Fig. 8 is a longitudinal sectional view illustrating the electrical conductor connection leading to the heaters. 85

Referring now more specifically to the drawings, the numerals 1 indicate railway ties of wood which, as usual, may be supported on a roadbed or on an elevated framework, the ties being retained in their positions relative to each other. The numerals 2 indicate the two stock rails of the railway track, and the numerals 3 indicate the two switch rails, the points of the switch rails being indicated by the numerals 4. The 90 switch rails are connected by the braces 5, and the switch may be actuated through a rod 50 which may be operatively connected to any suitable device for being shifted.

In the embodiments of the invention illustrated in the drawings electrical heaters are employed. These heaters utilize a heating filament as the source of heat. In the present case this filament may be of metal or other material of proper dimension to offer 100 sufficient resistance so as to become highly

heated on passage of the current. Metal resistance wire is illustrated.

In the embodiment illustrated in Fig. 2, each electrical heater includes an integral 5 heat-radiator block, or plate 6. This plate includes a downward extension 60, and is spiked to the tie 1, the extension 60 being inset in a shallow recess 7 in the upper face 10 of the tie. When the switch is open the switch rail is separated from the stock rail, there being an unobstructed air space between these two rails, which decreases in width as the switch rail approaches the stock rail. Obstructive foreign matter in 15 said air space may interfere with or prevent normal operation of the switch. In low temperatures ice and snow may accumulate in said space above the tie, and falling snow enters this space, and is deposited therein 20 above the tie. One of the main objects of the present invention is to assure the presence in said air space of a large amount of heat so as to cause accumulation of snow or ice therein to be melted, and adjacent ice 25 incrustation to be quickly loosened, and to assure presence of the heat in this space even though the wind be blowing strongly. The upper face 8 of the plate 6 is so disposed relative to the switch rail and the stock rail as to bound the air space between 30 these two rails at the bottom of said space, directly opposite the tie. In this wise the face 8 and the two rails 2 and 3 form a sort of pocket, the plate 6 and the rails being its 35 bounding walls. The plate 6 is composed of heat conductive metal, and the face 8 thereof radiates heat directly into the space referred to whenever the heater is in action. The switch rail and stock rail rest upon and make 40 direct contact with the face 8 and are of steel so that they too, as well as the face 8, are heated by the plate 6 and become heat radiator walls for the space between the two rails. The face 8 also is smooth and flat and serves 45 as a supporting bearing for the switch rail as the latter shifts in normal operation of the switch. Lengthwise of the track the plate 6 may be as long as the tie is wide, or even longer, and hence heat radiation into 50 the air space referred to comes from all points of the face 8, the plate acting to distribute the heat from the heat originating filament.

One effect of heating the rails and the 55 plate 6 is to cause expansion thereof, and advantage is taken of this effect to promote loosening of incrusted ice from the rails at points relatively remote from the heater. Expansion of the rails will occur not only at 60 the area of contact with the plate 6, but also beyond, toward the space between the ties. To augment this expansive effect a plurality of the heaters are located at short intervals longitudinally of the rails, as illustrated in 65 Figs. 1 and 2. Each of these heaters is also

located relative to the air space and relative to the stock rail and switch rail, as before explained. The expansive effect on the rails by this assemblage of heaters is cumulative, and the expansion tends to loosen the ice incrusted on the rails between the ties, so that it will drop to the roadbed or is shaken off the switch rail by vibration, as from operating the switch. The series of plates 6 give support to a great length of the switch rail 70 and positively heat a considerable length of the switch rail and the stock rail.

The depth of the extension 60 may be quite small compared with the depth of the tie, and hence the depth of recess 7 will not 75 be sufficient to weaken the tie unduly. Moreover the plate 6 reinforces the wooden tie 1. Between the tie 1 and the extension 60 an effective layer 9 of heat insulating material 80 may be located, to avoid charring of the walls of the recess. The radiator face 8 is not covered by and is exposed through this insulation. As the recess 7 is directly below the air space between the stock rail and the switch rail, the heater is at once in operative 85 position when disposed in said recess. It will be seen that the heating block forms a facing for that part of the tie which supports the rails and the loads of operation, and that the filament is embedded in this composite 90 tie, and heat insulated therefrom. Furthermore the tie serves to insulate the greater portion of the heating block from the outer air, and therefore promotes efficiency of heating of the radiator face 8.

In the embodiments illustrated the heaters are at the upper faces of the usual type of wooden railway ties. But it is to be understood that the heaters may be mounted on a different type of tie or pedestal rising from the roadbed, and might be located between the regular ties without departing from the broader aspects of this invention. It is believed, however, that disposition on the regular ties is to be desired because it permits the heaters to be located to best advantage relative to different parts of the length of the switch rail, and promotes the heat insulating effect.

On account of the heavy shocks and vibrations which the switch heater will have to endure in use, its construction should be such as to minimize injury, maintain the filament in operative condition and position under normal traffic and in low temperatures, and provide for efficient distribution of heat to the switch. In each embodiment illustrated the heating filament is encased in a strong, metal, heat radiator block, or plate. In the embodiment of Fig. 2, the filament passes through the extension 60 of the integral metal plate 6, of which the upper face 8 is an integral part. The plate or block 6 is of heat conductive material such as steel, and the heating filament lies between the upper and 100 lower faces of the plate 6.

lower surfaces of this block, and is mounted therein, as clearly shown in Figs. 4 and 7, in which 10 indicates the heating filament. The numeral 11 indicates a tube of heat conductive metal which is relatively flexible so as to be bent or wound, as into the zigzag shape illustrated. This tube may be of drawn steel. The filament 10 is insulated from the tube by being embedded in the centre of a mass of electrical insulating material 12 of a powdered, or granular character, as powdered mica or magnesia.

The mounting of the filament in the wound tube is best accomplished by first providing a straight tube of the drawn steel, and inserting a straight heating filament and the granular insulation into this straight tube, the filament being disposed in the centre of the mass of insulating material and so as to fill the tube, the ends of the tube being then closed, and having the filament projecting therefrom. By squeezing or swaging the wall of the tube, the granular material will be compacted and held in place around the filament, and the assemblage may then be wound into the desired shape with assurance that the filament will be held insulated from the tube in its new shape. Thereupon a mass of steel or other suitable heat conductive material is cast around the wound tube containing the heating filament. The cast jacket thus provided will be rigid and strong, will be in close heat conductive contact with the outer wall of the tube, and will reinforce and protect the tube and the insulating material therein, and prevent their being crushed or displaced under the heavy impacts of service. This jacket will also brace the windings of the tube in position relative to each other. By using a mold the heating block or plate 6, with the wound tube therein, may thus be produced in one operation. By casting a thin and wide block, the recess 7 in the tie, though shallow, will readily accommodate the extension 60, so that the upper heat radiator face 8 will be located in operative heating position. By the windings, origination of heat is distributed both lengthwise and cross-wise of the rails, so that the whole surface of the radiator face 8 is practically directly and quickly heated. Economy of current consumption and efficiency and quickness of heating follow by disposing the heating filament near and directly below the face 8 bounding the air space between the switch rail and the stock rail.

In the embodiment illustrated in Fig. 2, the plate 6 serves as the direct support of the railway rails 2 and 3, said rails resting thereon, the heating of these rails and of the air space therebetween being effected through the integral heating plate 6, which also thus serves as a tie plate.

In Fig. 3, the heating plate or block 13, which carries the heating filament is re-

movably mounted just beneath the separate rail supporting or tie plate 14. By this construction, the heaters may be applied to standard types of switches without removing the usual tie plates. In such case the heating block 13 may be flat and of the rectangular outline illustrated, adapted to be slid into and out of the recess 7 in the tie. The upper heat radiator face of the block 13 is held in close juxtaposition to the bottom of the tie plate 14. The tie plate of steel is therefore surely heated by the heating block 13, and thus the upper face of the separate tie plate 14 radiates heat directly into the air space between the stock rail and the switch rail, and the two rails are positively heated by the conduction of the metal. For purposes of repair, replacement and adaptation to standard railway switch equipment, the construction of Fig. 3 possesses important advantages.

In Fig. 4 the construction of the body of the heater is illustrated in detail. It is to be understood that this construction is similar to that illustrated in Fig. 3, but that the same construction may be employed for associating the filament with the integral heating block 6 illustrated in Fig. 2. In Fig. 4 the heating block is indicated at 13, being a flat, generally rectangular block corresponding to the similarly indicated block in Fig. 3. On the bottom and at the lateral sides of the block or plate 13 is the layer of heat insulating material 9, which may be asbestos. On the outside and around three sides of the insulating material is the metal shoe 16, having projections 17, which may be detachably connected to the block 13 by the bolts 18, as more particularly illustrated in Fig. 5. At the ends of the sides of the shoe are projecting ears 19, which may be bent into position against the upright sides of the tie for retaining the heating unit in place on the tie. The assemblage of heating block 13, insulation 9, and shoe 16, provides a heating unit in which the parts are detachably held together, so that either of them may be removed, as desired. Also these parts may be slid as one into the recess 7 of the tie beneath the tie plate 14. The windings of the filament and the tube 11 in which it is encased are also clearly illustrated in Fig. 4. When the form of heating unit employed in Fig. 2 is to be used the plate 13 of Fig. 4 may be made slightly thicker and provided with lateral flanges which may rest upon the upper surface of the tie, as illustrated in Fig. 2.

As will be seen on reference to Fig. 1, the filaments of the different heaters are connected to each other by the leads 20. These leads are flexible and of ample length so as to yield to vibration and permit longitudinal adjustment in distance between successive heaters. Also the leads should preferably

- 4
- be made waterproof and as non-oxidizable as possible in order to avoid corrosion. The opposite ends 21 of the tube 11 project from the passageway in the heating block, these ends, of course, being sealed by non-conductive material through which the filament projects. Each lead unit may comprise an electrical conductor or wire 22, enclosed in insulating material covered with varnished 5 cambric 23. The conductor 22 will have electrical contact with the projecting end of the filament 10, as indicated at 24. The numeral 25 indicates a copper sleeve surrounding the end 21 of the tube 11, this sleeve being sealed 10 to the tube 11 so as to form a water-tight joint. The opposite end of the copper sleeve 25 is swaged down onto the varnished cambric covered cable so as to seal it in a water-tight manner at this end. The opposite ends 15 of each of the leads 20 may be connected to the adjacent filaments and tubes 11 in the manner just described. The contact between the ends of the filaments 10 and the lead conductor 22 is conveniently made detachable. By this construction the conductors 22 are surrounded by a sheath, which protects them. The ends of the sheaths may readily be detached from the tubes 11 when desired. 20
- 20 Current may be supplied to the electric heaters from any suitable source of electric energy, through the conductor 30, the filaments on each side of the track being in series. At the opposite end of the assemblage the conductor 31 is grounded at 32. 25
- In an electric railway, current for the filaments may be taken off the "third rail", and in either instance suitable devices will be provided wherewith the filaments may be energized or de-energized so as to control the time for actuating the heaters. 30
- It will be noted that the plate 6 of Fig. 2, and the plate 14 of Fig. 3 serves as tie-plates resting on the relatively soft wooden tie and 35 also supporting the rails. The heating plate 13 of Fig. 3 is also adapted to serve as a tie plate, and protect the tie immediately thereunder. This supplementary tie-plate 13, therefore not only reinforces the tie where it is recessed, but it may be removed and inserted in rail supporting position without removing either the stock rail or the switch rail, and independently of the position of 40 said rails. In this wise the tie-plate construction of the railway is improved, the pair of superposed tie-plates 13 and 14 being adapted to act concurrently, either being capable of acting individually should injury occur to the other. If the tie-plate 14 be dispensed with, the plate 13 provides not only a heat radiator face, but a type of tie-plate on which the switch rail may slide in 45 normal operation of the switch. 50
- The operation will be apparent from the foregoing description. In freezing weather, 55
- the devices which control supply of current to the heating filaments will be set from the tower, or other suitable place of control, so as to electrically energize the filaments and cause them to raise the temperature of the 70 heat radiator plates 6, or 13, as the case may be. Any ice or snow which may have accumulated between the switch rail and the stock rail above the tie will be melted by the heat which is radiated directly into the space 75 between the two rails. Much of this snow and ice will be in direct contact with the heat radiator face of the heating plates so that there will be assurance of its being melted. The base and web of both the 80 switch rail and the stock rail will also be positively heated by contact with the heat radiator plate, so that the heat radiating area will be practically coextensive with the bounding area of the air space directly above 85 the tie. The fact that the wind may be blowing will be immaterial. Accumulated ice and snow will guard the heat radiating surfaces from the air currents. In case the heaters have been set in action in freezing 90 weather, and in contemplation of rain or a fall of snow, the snow will promptly be melted upon impingement on the heated radiator surfaces, and these same surfaces will prevent the formation of ice thereon. 95
- It will thus be seen that, in either instance, there is positive assurance that foreign matter, such as snow and ice, will be melted and thereby eliminated from obstructive position between the switch rails or will be prevented 100 from obstructively accumulating between said rails. 105
- It will be perceived that in each modification illustrated the heating filament is shielded from the wind by a mass of heat conductive metal having a heat radiator face exposed to the outer air and forming a bounding wall of the air space between the switch rail and the stock rail. In Fig. 2, this shield is formed by the plate 6; in Fig. 3, it is formed by the superposed plates 13 and 14. When the plate 14 is omitted the shield will be formed by the plate 13. As illustrated in Fig. 3, the shield plate 13 carries the filament and is movable 110 into and out of position in the shield without displacement of the rails from the upper shield plate 14. 115
- Since certain changes may be made in the above construction, and different embodiments of the invention could be made without departing from the scope thereof, it is intended that all matter contained in the above description, or shown in the accompanying drawings, shall be interpreted as 120 illustrative and not in a limiting sense. 125
- It is also to be understood that the following claims are intended to cover all of the generic and specific features of the invention herein described, and all statements of the 130

scope of the invention which, as a matter of language, might be said to fall therebetween.

Having described our invention, what we claim as new and desire to secure by Letters Patent is:

1. In a railway switch, in combination, a railway tie having a recess in its upper face directly below the air space between the stock rail and the switch rail, a tie reinforcing, heat-radiator plate inset in said recess and heat insulated from the walls of said recess, and a heating filament carried by said plate between its upper and lower surfaces.

2. In a railway switch, in combination, a railway tie having a recess in its upper face directly below the air space between the stock rail and the switch rail, a tie reinforcing, heat-radiator plate inset in said recess and heat insulated from the walls of said recess, and a heating filament carried by said plate between its upper and lower surfaces, and a rail supporting plate of heat conductive metal bridging said recess and in close superposed relation to said reinforcing plate.

3. In a railway switch, in combination, a railway tie having a recess in its upper face directly below the air space between the stock rail and the switch rail, a tie reinforcing, heat-radiator plate inset in said recess and heat insulated from the walls of said recess, a heating filament carried by said plate between its upper and lower surfaces, and a rail supporting plate of heat conductive metal bridging said recess and in close superposed relation to said reinforcing plate, said heat-radiator plate being removably mounted between said supporting plate and said tie, and having means adapted to cooperate to retain it in heating position.

4. In an apparatus of the character described, in combination, a relatively flexible, bent, metal tube having a heating filament therein electrically insulated therefrom, and a rigid heat-distributive jacket of metal in close contact with the windings of said tube and bracing the windings in position relative to each other, the ends of said tube projecting from said jacket, said jacket being relatively thin and wide and having an upper heat radiator face, a layer of heat insulating material through which said upper face is exposed, and a shoe detachably connected to said jacket adapted to retain said insulating material in place.

5. In an apparatus of the character described, in combination, a heating filament, a tube of heat conductive material in which said filament is contained, a heat distributive tube reinforcing plate of heat conductive metal in which said tube is encased, and a protective shoe heat insulated from said plate and adapted to expose a heating face of said plate.

6. In an apparatus of the character described, in combination, a heating filament, a tube of heat conductive material in which said filament is contained, a heat distributive tube reinforcing plate of heat conductive metal in which said tube is encased, and a protective shoe heat insulated from said plate and adapted to expose a heating face of said plate, said shoe being removably connected to said plate and having bendable shoe-holding ears.

7. In an apparatus of the character described, in combination, a tie having in its upper face a recess of small depth relative to the depth of the tie, a rail supporting plate of heat conductive metal resting on said tie immediately above said recess, a heat distributive plate of heat conductive metal lying in said recess with its upper face close to the lower face of said supporting plate, and a heating filament mounted on said distributive plate.

8. In an apparatus of the character described, in combination, a tie having in its upper face a recess of small depth relative to the depth of the tie, a rail supporting plate of heat conductive metal resting on said tie immediately above said recess, a heat distributive plate of heat conductive metal in said recess with its upper face close to the lower face of said supporting plate, and a heating filament mounted on said distributive plate being slidable between said tie and supporting plate into and out of said recess.

9. In an apparatus of the character described, in combination, a tie having in its upper face a recess of small depth relative to the depth of the tie, a rail supporting plate of heat conductive metal resting on said tie immediately above said recess, a heat distributive plate lying in said recess with its upper face close to the lower face of said supporting plate, and a heating filament mounted on said distributive plate, said distributive plate being slidable between said tie and supporting plate into and out of said recess and having a protective shoe heat insulated therefrom.

10. In an apparatus of the character described, in combination, a tie having in its upper face a recess of small depth relative to the depth of the tie, a rail supporting plate of heat conductive metal resting on said tie immediately above said recess, a heat distributive plate lying in said recess with its upper face close to the lower face of said supporting plate, and a heating filament mounted on said distributive plate, said distributive plate being slidable between said tie and supporting plate into and out of said recess and having a protective shoe heat insulated therefrom, said shoe detachably connected to said distributive plate and having devices adapted to cooperate with the

tie removably to retain the distributive plate in superposed relation to said supporting plate.

11. In an apparatus of the character described, in combination, a stock rail, a switch rail, a tie, & heat conductive tie-plate inset in the upper face of said tie directly below the space between said rails, and a tie-plate heating filament heat insulated from the 10 wall of the recess in the tie in which it is inset.

12. In an apparatus of the character de-

scribed, in combination, a stock rail, a switch rail, a tie, and a pair of heat conductive tie-plates in superposed relation to each other, the lower of said plates being removable from said tie independently of the position of said rails, and a heating filament carried by and removable with said lower plate.

In testimony whereof we affix our signatures.

CHARLES W. MOFFETT.
MARK R. BRINEY.
